UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-RIGGING FOR RAILWAY-CARS.

1,231,053.

Specification of Letters Patent. Patented June 26, 1917.

Application filed November 30, 1914. Serial No. 874,690.

To all whom it may concern:

Be it known that I, JOHN F. O'CONNOR, a citizen of the United States, residing at Chicago, in the county of Cook and State 5 of Illinois, have invented a certain new and useful Improvement in Draft-Rigging for Railway-Cars, of which the following is a full, clear, concise, and exact description, reference being had to the accompanying 10 drawings, forming a part of this specification.

This invention relates to improvements in draft riggings for railway cars.

An object of the invention is to provide 15 a draft rigging for railway cars which consists of few parts of simple construction, and one which avoids the necessity of stop castings but permits of the use of slideable keys.

In the drawing forming a part of this 20 specification, Figure 1 is a part side elevation, part vertical sectional view of a draft rigging embodying my improvements and Fig. 2 is a horizontal sectional view taken substantially on the line 2—2 of Fig. 1 but 25 showing the gear under full buff and Figs. 3 and 4 are vertical sectional views taken substantially on the lines 3—3 and 4—4 respectively of Fig. 1.

In said drawing, 10—10 denote the center 30 sills or other draft members adapted to receive the shocks of the draft rigging, said sills, as shown, being each provided with elongated slots 11 and 12. The draw bar is designated by the reference 13, the same 35 being provided with the usual upper and lower front shoulders 14 with which are adapted to coöperate inturned shoulders or gibs 15 formed on the inner sides of the front ends of the arms 16 of the yoke 17, the 40 arms 16 being united by the rear portion 18, said yoke being also provided with a rear filler or abutment 19. The front ends of the arms 16—16 are also provided with side wings or walls 20 which overlap the sides 45 of the draw bar butt and serve to strengthen the shoulders 15.

Within the yoke are mounted a front follower 21, rear follower 22 and nested springs 23 intermediate said followers. Each of the

followers 21 and 22 is transversely slotted 50 and receives therethrough a key 24, said keys being slideable in the slots 11 and 12 in the center sills. The front key 24 also passes through slots 25 in the side walls of a rectangular band or hood 26 which surrounds 55 the yoke, front follower 21 and a portion of the draw bar butt. As will be apparent, the hood or band 26 moves with the front key 24.

Secured to the inner sides of the sills 60 10—10 and intermediate the slots 11 and 12, are spring guide plates 27 each of which is preferably in the form of a plate bent to have vertical flanges 28 adapted to be secured to the sills by rivets 29, horizontally 65 extending portions 30 and inner vertical wall 31. These members 27 are so arranged that they guide the springs, prevent buckling thereof and also serve to maintain the gear in central position, this latter result being 70 accomplished because of the fact that the inner coil of the nested springs is mounted on bosses 32 formed on the inner sides of the front and rear followers.

The operation of the device is as follows: 75 Under buff, the rear key 24 is held stationary and consequently the rear follower 22. Upon inward movement of the draw bar, the front follower 21, front key 24 and hood or band 26 are moved inwardly, thus compressing the springs against the rear follower 22, the inward movement being limited by the engagement of the front key 24 with the rear ends of the slots 12. Under 80 draft, the front follower and hood 26 are held stationary by the front key 24 and the rear follower is pulled forwardly by the draw bar on account of the interengaging shoulders 14 and 14. 85

I claim:

1. In a draft rigging for railway cars, the combination with draft sills, of a draw bar, a yoke, the draw bar and yoke having coöoperating shoulders, a front follower, a 90 rear follower, a cushioning device between said followers, keys supporting said followers, said keys being mounted in elongated 95

slots in said sills, and a hood surrounding said yoke and the draw bar butt and movable with one of said keys.

2. In a draft rigging for railway cars, the combination with the draft sills, of a draw bar, a yoke, the draw bar and yoke having coöperating shoulders, a hood en-

circling said yoke and draw bar, a front follower, and a key passing through said follower and said hood.

JOHN F. O'CONNOR.
